UNITED STATES PATENT OFFICE

JOHN B. BERRIGAN, OF OAK PARK, AND JOSEPH HARRINGTON, OF RIVERSIDE, ILLINOIS, ASSIGNORS TO THE PRESS & DRIER CO., OF CHICAGO, ILLINOIS, A CORPORATION OF ILLINOIS

SLUDGE DRIER

Application filed June 9, 1930. Serial No. 460,051.

This invention relates to machines for drying sludge, peat, clay and any plastic fibrous or granular material having an unusually high moisture content. The invention is an improvement on the machines shown in the patents of John J. Berrigan and John B. Berrigan, Numbers 1,770,727 and 1,792,064, filed on May 9, 1928, and June 14, 1929, respectively.

10 The constructions disclosed in the above patents are continuously operable machines intended to receive material, such as the sludge from sewage disposal plants, and to rapidly dry the material as it is passed through the machine. Highly heated surfaces are provided, over which the material is rubbed to almost instantaneously release moisture therefrom without burning the material to such an extent as might lessen its 20 value as a fertilizer.

The objects of the present invention are to provide improvements which result in a more rapid treatment of the material; to provide a machine with increased capacity, improved means for applying heat and removing moisture, an improved feed mechanism, and improvements in the specific design of the rubbing blades and co-acting guide elements therefor.

30 The objects of the invention are accomplished by the construction illustrated in the drawings in which:—

Figure 1 is a side elevation of the improved machine.

35 Fig. 2 is a front elevation partly in section, as indicated by the line 2—2 in Fig. 1.

Fig. 3 is a sectional view taken on the line 3—3 of Fig. 2.

40 Fig. 4 is a sectional detail taken on the line 4—4 of Fig. 1, illustrating the method of mounting channel guides within which material is dried.

Figures 5 and 6 are enlarged sectional details of the guide members shown in Fig. 4, but taken on the lines 5—5 and 6—6 of Fig. 8.

45 Fig. 7 shows one of the guide elements in side elevation.

Fig. 8 is an end view of an assembled 50 group of guide elements.

Fig. 9 is an enlarged fragmentary sectional detail taken on the line 9—9 of Fig. 7.

Fig. 10 is a perspective view of one of the rubbing blades which are reciprocated in the channels formed by the guide elements, 55 shown in Figures 4 to 9 inclusive.

The means in general employed for carrying out this invention include a combustion chamber, preferably arranged for burning gas or oil, and having mounted therein a 60 compact assemblage of cast plates formed to provide vertical passageways for the material operated upon, and independent horizontal passageways for the products of combustion.

55 Outlets are also provided for material-carrying passageways for the release of steam from the material, the steam being carried along with the products of combustion to a stack. The draft through the stack is supplemented by the action of a blower for the purpose of maintaining a fixed and rapid flow of air, moisture and the products of combustion from the apparatus.

65 The vertical channels in the material-treating part of the apparatus receive the material from a feed hopper at the top of the construction and such material is rubbed over the surfaces of the channels by means of a series of blades fitting in the channels, which are 70 rapidly and alternatively lifted and then allowed to descend by means of motor driven eccentrics mounted above the machine.

75 The function of the reciprocating blades is to rub the material acted upon over heated 85 surfaces and maintain a proper rate of movement of the material through the drying channels for the purpose of expelling moisture from the material, without subjecting the material to a high temperature to the 90 extent that it would injure the product.

85 Referring to the drawings, Figures 1, 2 and 3 show the general arrangement of the machine, its most important units being the channel, material-treating elements 1 in which the rubbing blades 2 are reciprocated, material hoppers 3 and feed mechanism 4 therefor, a lifting mechanism 5 for the blades 2, a furnace 6 and screw conveyors 7 for removing the dried material. The drive mech- 100

anism for the machine, which is mounted on the top thereof, is arranged for driving a plurality of similar drying units, which may be noted from Figure 2.

The combustion chamber 8 of each unit is formed by a furnace structure 6 mounted upon casters 9, resting in channel tracks 10. The furnace 6 is formed to fit against the channel material unit 1 but is mounted upon the tracks 10 to facilitate assembly and access to it and the cooperating structure. At the opposite side of the channeled unit 1 is a semi-cylindrical furnace structure 11, supported on fixed horizontal beams 12 to the casters 13 carried by the furnace 11. The furnace 6 is provided with a horizontal partition 14; thus the products of combustion travel from the combustion chamber, through horizontal passageways 15 in the channel unit 1, into the chamber 16 of furnace structure 11. From this chamber the products of combustion flow in a reverse direction through the passageways 17 in unit 1 into the lower chamber 18 of furnace 6. The stack outlet is indicated at 19. A motor-driven blower 20, Figure 2, creates the necessary draft through the outlets 19 to stack 21. Steam from the material which is dried also flows with the products of combustion. The steam leaves the vertical channels 22 of unit 1 through the inclined outlets 23, Figure 7, formed in the channel members 24 which compose the unit 1.

The unit 1 is supported upon piers 25, Figure 3, and rests upon the adjustable wedges 26 at the top of the piers. These wedges may be moved inwardly or outwardly by the screws 27 and thus, by engaging the inclined surfaces 28 at the bottom of the channel members, control the position thereof with reference to the interfitting furnace structures.

The piers 25, as shown in Figure 1, support vertical frame pillars, or channel members 29, which are tied together by the channel beams 30 above the furnace. The drying unit 1, formed by channel castings 24, is held in assembled position between the frame members 29, Figure 4, by the screws 31 and 32.

The surfaces of plates 24, forming the channels 22, are provided with depressions, or countersinks, 33, for momentarily retaining the wet material until dragged out of such pockets by the action of oncoming material which is rolled by the reciprocating blades 2.

The material rubbing blades 2, which contact with the inner channel surfaces of the members 24, are provided with staggered openings 34 into which the material acted upon is squeezed, enabling the blades to better drag the rubbed material along the heated surfaces provided by the plates 24.

The lifting mechanism for the blades 2 includes crossheads 35 upon which shoulders 36, at the upper end of blades 2, rest. Crossheads 35 are reciprocated by pitmen 37, Figure

1, mounted upon the eccentrics 38. Shaft 39, to which the eccentrics are keyed, is driven through gearing in gear box 40 and which receives motion from an electric motor 41.

The material to be treated is continuously discharged into the hoppers 3 from which it is delivered, according to the rate of operation of the machine, to the channels 22 in units 1, through ports 42, Figure 3, at the bottom of hoppers 3. The rate of feed of the material into the units 1 is under the control of an oscillating pusher 43 in each hopper.

Arm 44 which carries the pusher 43 is oscillated by an adjustable ratchet feed 45 driven by a pitman 46 on eccentric 47 fast to a horizontal shaft 48. The shaft 48 is belted to the driven shaft 39. Shaft 49, which carries ratchet 50, is also provided with an eccentric 51 for pitman 52 connecting the eccentric with supporting arm for the pusher 43.

The operation of the drier, above described, includes an action which is characteristic of the process and the constructions disclosed in the patents above referred to, in that the material under treatment is subjected to a back and forth rubbing between reciprocating blades and co-acting surfaces, while the material is progressively fed from end to end of the drying unit. In the former construction, the sludge was subjected to the direct action of the products of combustion. In the present arrangement, the products of combustion are utilized to heat the material indirectly through the walls of the heating unit, which walls are provided for conduits for the products of combustion. The vertical channels of the drying unit, in which the reciprocating blades travel, are also in communication with the combustion chamber, but since the moisture of the sludge is converted into steam under pressure, the flow from the sludge-carrying channels is outwardly into the lower pressure of the products of combustion.

The sludge to be treated flows into the hoppers 4 from conduits, or other supply means not shown, and measured quantities of the sludge in the hoppers is forced through ports 42 to spaces between the upper ends 115 of blades 2, above the drying unit 1. The material flows by gravity and the action of blades 2 through the shoulders provided by the staggered openings 34 therein into the spaces 22 between the plates 24 forming the unit 1. The blades 2 move downwardly because of their own weight and the weight of the material in contact therewith, as permitted by the downward movement of crossheads 35. When the crossheads move upwardly, under the action of eccentrics 38, the blades are drawn upwardly.

The steam, which is generated in the sludge as it is rolled over the surfaces of plates 24 and the blades 2, is released into the combus- 120

tion chamber 8 and the chamber 16, Figure 3, through the inclined outlets 23 in plates 24. The drying is rapidly effected. The dried material drops from the channels 22 5 into the conveyors 7 which carry the material to mixing or sacking apparatus, not shown.

The machine is designed with particular reference to accessibility to all of its parts, so that in case of breakage, repairs to any one 10 unit may be rapidly effected. It is also designed for continuous operation and any desired capacity, according to the output of sewage disposal plants.

In order to remove one of the plates, it is 15 only necessary to unbolt the furnace sections from the frame structure and roll these sections out of the way, and then, by means of the bolts 32 and 31 which clamp the plates 24 in place, these may be separated and re- 20 moved. The blades 2 may be lifted out of the apparatus when requiring replacement.

Although but one specific embodiment of 25 this invention has been herein shown and described, it will be understood that certain details of the construction shown may be altered or omitted without departing from the spirit of this invention as defined by the following claims.

We claim:

30 1. A drier comprising a drying unit having a plurality of vertical channels, reciprocating elements movably mounted within said channels for the purpose of feeding and rubbing the material operated upon, said drying unit being provided with horizontal channels therethrough for the purpose of conducting a heating medium, a furnace structure formed of two parts, each part secured to one side of said drying unit in communication with the horizontal channels in the unit and each part of the furnace being 40 mounted upon casters.

2. In a drying apparatus, a unitary structure having a series of vertical channels for 45 receiving material to be operated upon, blades suspended within said channels, said blades being provided with projections at their upper ends, crossheads upon which said projections rest and means for reciprocating said 50 crossheads.

Signed at Chicago this 6th day of June, 1930.

JOHN B. BERRIGAN.
JOSEPH HARRINGTON.
